UNITED STATES PATENT OFFICE

162,876

TEXTILE FABRIC

Henry A. Portong, Manhasset, N. Y.

Application August 11, 1950, Serial No. 11,726

Term of patent 3½ years

(Cl. D92—1)

To all whom it may concern:

Be it known that I, Henry A. Portong, a citizen of the United States of America, residing in Manhasset, county of Nassau, and State of New York, have invented a new, original, and ornamental Design for a Textile Fabric, of which the following is a specification, reference being had to the accompanying drawing, forming part thereof, wherein, the figure on the drawing is a plan view of a textile fabric, showing my new design, a design unit of which is repeated between the selvage edges of the fabric as shown.

I claim:

The ornamental design for a textile fabric, substantially as shown and described.

HENRY A. PORTONG.
